UNITED STATES PATENT OFFICE

JAMES HALL TAYLOR, OF CHICAGO, ILLINOIS

UNIVERSAL RING-ROLLING MACHINE

Application filed December 10, 1923. Serial No. 679,573.

This invention relates to a ring rolling machine or mill of that type in which a circular billet of metal or the like is rolled to produce the desired size, thickness, width and compactness.

It is an object of this invention to provide a machine of this character which is universal in character in that different sizes of rings may be rolled; in which said rings can be reduced to any desired thickness or width by an easy rolling action; in which a beaded or ribbed ring may be rolled and in which a ring may be flanged.

It is a further object of this invention to provide an arrangement of rolling elements defining substantially a closed way for acting substantially upon the same cross-section of a ring, that will avoid abrading the metal; that are readily adjustable, and that will avoid fringing or slivering the metal, and that will avoid bulging or distorting the ring.

It is a still further object of this invention to provide a ring support with rolling elements that are readily adjustable for retaining different sized rings and which is automatically adjustable with respect to curved abutments so designed as to always maintain said rollers in proper relation to the ring that is being rolled.

With these and other objects in view which will become more apparent in the following description and disclosures, this invention comprises the novel mechanism and combinations hereinafter described and more particularly pointed out and defined in the appended claims.

In the accompanying drawings which illustrate a preferred embodiment of this invention and in which similar reference numerals refer to similar features in the different views:

Figure 1 is a top plan view of the rolling mill with parts omitted.

Figure 2 is a vertical sectional view of the machine.

Figure 3 is a sectional view upon the line 3-3 of Figure 1 looking in the direction of the arrows.

Figure 4 is a section upon the line 4-4 of Figure 2 showing parts in elevation.

Figure 5 is a sectional view upon the line 5-5 of Figure 1.

Figure 6 is a sectional view upon the line 6-6 of Figure 2 showing parts in elevation with parts omitted.

Figure 7 is a fragmentary part elevational and part sectional view of a modified form of rolling mill.

Figures 8 and 9 are fragmentary sectional views of a further modification of a rolling mill illustrating the method of flanging a ring.

Figure 10 is a sectional view of a tapered roll and an elevational view of a cylindrical roll illustrating their overlapping relation.

Referring to the drawings, there is shown a suitable frame for supporting the various parts of the machine comprising a horizontal support or table 1 upon which a ring support 2 is slidably secured. In the present instance, the ring support has underhanging flanges that engage the side margins of the table 1 as shown in Figure 3. This ring support is formed with a plurality, four in the present instance, of radiating arms 2^a which are equally spaced. Guide grooves 3 (Figure 5) are formed in each arm, and slideable shoes 4 and 4^a are positioned in said grooves. The inner ends of these shoes are bifurcated in a horizontal plane and rolling element 5 having lower flanges 5^a are journaled in said bifurcations. The shoes 4^a are provided with outwardly projecting ribs 6 which are always in engagement with the cam members or curved abutments 7 for any adjustment of the shoes and support 2 as will later appear.

The curved abutments 7 are bolted to a support constituting a part of the machine frame. Screws 9 having inner reduced ends firmly secured radially of each shoe are provided. These screws extend through spaced abutments 10 upon the ring support. Gears 11 having inclined teeth are threaded upon the screws 9 between the abutments 10. By rotating the said gears, the screws are longitudinally shifted for adjusting the shoes and rolling elements.

A pair of fluid cylinders 1^a are supported beneath the table 1, and fluid operated plungers 1^b in said cylinders engage abutments 2^c upon the ring support 100

2 for urging the same against the cam abutments 7.

Mechanism has been provided for simultaneously rotating the gears 11 and shifting the screws. In referring to Figure 1, it will be observed that a pair of parallel shafts 12 are journalled in suitable brackets 13 attached to the sides of the frame of the machine. Gears 14 (Figure 3) are secured upon these shafts; one in mesh with each gear 11; suitable slots being provided in the arms 2^a for this purpose. The gears 14 have inclined teeth corresponding to the inclination of the teeth on the gears 11 in order that they may properly mesh. Gears 15 are secured upon the outer ends of the shafts 12, and mesh with idler gears 16 which are driven by a central gear 17 upon a shaft 18 which may be connected to some power means as a driving motor, or hand crank. It will be obvious that by rotating the gear 17, the shafts 12 are simultaneously rotated for simultaneously adjusting the rolling elements 5 for varying the circle defined thereby. The ring 19 which it is desired to roll is sustained between these rollers by the flanges 5^a thereof as shown in Figure 1. Obviously by adjusting the rollers 5 different sized rings may be supported, and as these rollers bear against the outer periphery of the ring no matter what its diameter may be, the same will be accurately held and guided as it is being rolled.

It will be understood that by adjusting the rollers 5, the ring supporting circle defined thereby will be varied. As the supported ring must always contact the cylindrical roll 43 which rotates upon a fixed axis, the center of such circle will shift with respect to the roll 43 as the diameter of such circle is varied. This shifting of the center of the circle with respect to the roll 43 is effected by sliding the support 2. As the circle increases, the rolls supported by the shoes 4^a which may be termed the forward rolls will move rearwardly and outwardly. In order that such rolls may always firmly engage the ring, the cam or curved face of the abutments 7 slope or curve outwardly and rearwardly in a similar manner. In other words, the slope or curvature of the abutments 7 follows the movements of the forward rolls during their adjustment in conjunction with the automatic shifting of the support 2. The design of the curvature of the abutments 7 may be readily determined by drawing a plurality of different sized circles tangent to the same point of the roll 43 and plotting the curve or slope defined by the movement or different positions of the forward rolls 5 or the ends of the ribs 6.

A shaft bearing 20 is slidably mounted in the frame of the machine as shown in Figure 2 and is acted upon by a fluid plunger 21. A sectional inclined shaft 22 is journalled in

said bearing and provided with a bevelled gear 23 upon its lower end and a tapered or conical roll 24 upon its upper end. A slideable collar 22^a normally sheathes the junction of the two shaft sections which may be joined as shown in Figure 7. This structure allows the roll 24 to be readily withdrawn from its bearing for the substitution of another roll.

A second slideable bearing 25 is suitably supported above the ring support 2 and is normally under the influence of a fluid operated plunger 26. An inclined shaft 27^a is journalled in this bearing and is provided with a bevelled gear 28 upon its upper end and a conical or tapered roll 29 upon its lower end which is positioned above the conical roll 24. The outer ends of these tapered rolls 24 and 29 are provided with concave recesses 30 to provide clearance for the inner peripheral roll and a clear cut rolling edge that prevents fringing of the ring. These tapered rolls are adapted for engaging the sides of the ring during the rolling process as shown in Figure 2.

An interior roll 31, shown in the present instance as of cylindrical form for engaging the inner periphery of the ring 19 that is being rolled, is rotatably and removably mounted upon the upper end of a slideable support 32 secured at its lower end in a head 33 which in turn is anchored to a piston 34 by means of a pair of rods 35. The piston 34 operates in a fluid cylinder 36, movably supported by a bracket 37 attached to the frame of the machine. The head 33 of the slideable support 32 is provided with a depending cylinder 38 into which a stationary piston 39 extends, which is suitably supported upon the closed end of the cylinder 36. There is hence a double fluid action upon the support 32. By varying the pressure in either cylinder 36 or 38, the support 32 may be vertically adjusted. The roller 31 is also adapted to be urged against the ring 19 by a fluid operated plunger 40 located in the cylinder 41 and pressing upon a slideable bearing 42 adjacent the support 32. The bearings 42 and 20 are slideable toward the right as viewed in Figure 2, the gear 54 with which the gear 23 is in mesh sliding on its shaft 52 during such adjustment. The bearing 20 may be adjusted relative to the bearing 42 by means of a set screw 20^a. These fluid operated plungers for urging the rollers to their work are old and well known and do not form a part of this invention except in so far as they may cooperate therewith.

The aforementioned exterior roll 43 which is shown in the present instance as of cylindrical form is loosely journalled upon a shaft secured in a suitable bearing support 44. A pair of oppositely disposed gears 45 (Figure 4) are journalled in the bearing 44. These gears 45 are provided with cylindrical

friction hubs or elements 45^a (Figure 2) that engage the outer periphery of the roll 43 at spaced points of about 90° upon converging tangents thus producing a form of friction gearing that exercises a wedging action upon the roll 43. The gears 45 mesh with a common driving gear 46 secured upon a vertical shaft 47 journalled in the bearing 44, and in the movable bearing 25, the upper end being journalled in a bearing lug 48 on the machine frame. The vertical shaft supports a bevel gear 49 in mesh with the gear 28 of the upper tapered roll 29 and forms the driving means therefor. The lower end of the vertical shaft 47 supports a second bevelled gear 50 in mesh with a bevelled gear 51 upon the driving shaft 52 to which power may be applied through a gear 53 thereon. The previously mentioned bevelled gear 54 that meshes with gear 23 is supported intermediate the ends of the shaft 52. It is accordingly obvious that the driving shaft 52 with the described gears affords means for simultaneously rotating the tapered rolls and the exterior roll 43. As there will be more or less of a wedging action between the roll 43 and the friction elements 45^a as above explained on account of the pressure against the roll 43 which is loosely mounted upon its shaft for movement transversely of its axis as shown in Figure 4, the rotatable friction driving effect will be increased, so that said friction hubs may exercise a strong rotative effort upon the roll 43 in its operative relation with the ring to be rolled. The tapered rolls and the outer cylindrical roll 43 are designed to approximately rotate at the same peripheral velocity so that there will be no appreciable drag or abradant action upon the ring that is being rolled.

If it is desired to roll a ring with a bead or rib, one of the tapered rolls may be stepped as shown in Figure 7, whereby a reduced conical or tapered portion 24^b is formed upon the lower tapered roll 24^a. The supporting shaft for the roll 24^a is also shown as made in sections just as the shaft 22; the lower roll being secured upon a section 55 having a mortise and tenon connection with the section 56, the juncture being sheathed by a slidible collar 55^a; the lower section being freely slidible from its bearing 20. Accordingly the tapered roll and its stub shaft may be readily substituted for the roll 24 shown in Figure 2, if the rolls 24 and 24^a are not readily removable for interchanging purposes.

In some cases, it may be desired to form a flange upon a ring. In Figures 8 and 9 I have illustrated an arrangement for accomplishing such a purpose. In such a case, I use as a part of the apparatus, a ring member 19^a having a rabbet extending from one of its margins, preferably the upper inner margin. The ring 57 that it is desired to flange is positioned in the rabbet of the ring

member with the margin to be flanged extending beyond the inner periphery of the ring 19^a. This extending margin may be reduced as shown if so desired. The interior cylindrical roll 31^a has a lower bevelled surface and it is shown above the ring 57 with a part extending into the recess in the end of the tapered roll 29. Now by properly varying the pressure, the roll 31^a may be drawn down bending the projecting portion of the ring 57. The roller 31^a is adapted to be drawn down into the position shown in Figure 9. The supporting ring is engaged by the tapered rolls 24 and 29, the latter of which also engages over the ring 57 and by the exterior cylindrical roll 43, and as these rolls are rotated as before explained the rings 19^a and 57 will be rotated conjointly and the interior cylindrical roll 31^a will flange the ring 57 against the inner periphery of the supporting ring 19^a as shown in Fig. 9. It will of course be understood that the roller 31^a may be substituted for the roller 31 when such a flanging operation is desired. It is for this reason that the tapered roll 29 is shown in Figure 2 as provided with an end recess.

In referring to Figures 2, 7 and 10 it will be noted that the interior cylindrical roll 31 overlaps the end of the tapered roll 24, and that it is in turn overlapped by the upper tapered roll 29. The exterior cylindrical roll 43 overlaps the upper tapered roll 29, and is in turn overlapped by the lower tapered roll 24. It will be noted that these four rolls define substantially a closed way through which the ring rotates, and that they act upon the ring in substantially the same plane of cross-section somewhat in the nature of a die. This particular structure is important since it prevents outward bulging of the ring, injurious distortions and waste which continually arise where such rollers are circumferentially spaced of the ring. It is therefore evident that the rolls acting upon the ring that is being rolled may be readily adjusted as shown in Figure 7 so that the dimensions of the metal of the ring may be reduced to any desired size. It will be appreciated that if the rolls were circumferentially spaced and did not define a closed way, the ring might bulge between such circumferentially spaced rolls and become so distorted that it would result in waste, especially if light rings were being rolled. Such bulging and distortion of the rings will be substantially obviated in the use of my improved construction. Such a construction will also avoid fringing and slivering of the rings. It will of course be understood that the rolls are contracted and expanded through the fluid operated pistons or motors, as is well known in the art.

In the operation of this machine, the interior cylindrical roll may be adjusted to admit the ring to be rolled. Likewise the ta-

pered rolls may be adjusted through the fluid system if necessary to admit the ring therebetween. The ring to be rolled is then placed between the rolls 5 on the ring support so as to rest upon the flanges 5^a thereof. The roll 31 may then be properly adjusted to the position shown in Figure 2 through the fluid system. If the rollers 5 define too large or too small a circle to receive the ring, they 10 will of course be first adjusted in one direction or the other as the case may be by rotating the shaft 18. With the ring in the position shown in Figures 1 and 2, the driving shaft 52 may be rotated to rotate the tapered 15 rolls 24 and 29 and the exterior cylindrical roll 43 in the direction the rolled ring is to be rotated. Rotation of these rolls will cause the ring 19 to revolve for the purpose of properly forming the same as to the desired size and thickness. As occasion requires, the ring supporting rolls 5 may be adjusted to properly support the ring. During each such adjustment, the fluid operated 20 plungers 1^b will automatically force the ring 25 support 2 against the cam abutments 7 as is obvious, and the fluid system will automatically adjust the reducing rolls 24, 29 and 31.

It will accordingly be apparent that this improved machine will roll rings without 30 causing distortion thereof. Besides it has a wide range of utility in that it is susceptible of rolling rings of different sized diameters and reducing the metal thereof to any desired thickness and width, of rolling rings with 35 beads or ribs by substituting a single and differently formed roll, and of rolling rings with a flange by substituting a bevelled peripheral roller and utilizing a rotatable ring support for the ring to be rolled.

40 I am aware that many changes may be made, and numerous details of construction may be varied through a wide range without departing from the principles of this invention, and I therefore do not purpose limiting 45 the patent granted hereon, otherwise than necessitated by the prior art.

I claim as my invention:

1. In a machine for rolling rings, a pair 50 of tapered rolls for engaging the sides of a ring, an interior roll for engaging the inner periphery of the ring, an exterior roll for engaging the outer periphery of the ring, said rolls defining a closed way and having mutually overlapping parts when properly adjusted for the purpose set forth.

2. In a machine for rolling rings, a pair 55 of rolls for engaging the sides of the ring, an interior roll for engaging the inner periphery of the ring, an exterior roll for engaging the outer periphery of the ring, and rotatable friction elements engaging said exterior roll at spaced points upon converging tangents whereby a wedging action will be imparted to said exterior roll.

65 3. In a machine for rolling rings, a pair of

rolls for engaging the sides of the ring, an exterior roll loosely journalled for slight transverse movement of its axis, and a pair of rotatable friction elements engaging said exterior roll upon spaced points defined by converging tangents.

4. In a machine for forming rings, a pair 70 of tapered rolls having recesses in their ends to provide clearance adapted for engaging the sides of a ring, and a periphery engaging roll shiftable transversely of the recessed ends of said tapered rolls.

5. In a machine for rolling rings, a pair 75 of tapered rolls for rolling the sides of the ring, an exterior roll for engaging the outer periphery of the ring, and an interior roll for engaging the inner periphery of the ring, and means for axially shifting said interior roll.

6. In a machine for rolling rings, a pair 80 of tapered rolls for engaging the sides of the ring, a roll for engaging a periphery of said ring and means for axially shifting said last mentioned roll.

7. In a machine for rolling rings, a pair 85 of tapered rolls having recessed ends, and a shiftable roll adapted for entering said recessed ends for the purpose set forth.

8. In a machine for forming rings, a pair 90 of tapered rolls for engaging the sides of the ring, a flanging roll and means for axially shifting said flanging roll with respect to said tapered rolls.

9. The combination with a ring member 95 having a marginal rabbet adapted for receiving a ring to be flanged, said ring adapted to project beyond the adjacent periphery of said ring member, of a pair of rolls for engaging the sides of the ring member with one roll contacting said ring and an axially movable flanging roll adapted for rolling the projecting portion of said ring against said ring member.

10. The combination with a ring member 100 having a rabbet upon its inner margin adapted for receiving a ring to be flanged with a portion of said ring extending interiorly of said member, of a pair of rolls for engaging the sides of said ring member with one roll overlapping said ring and an interior flanging roll movable transversely of said other rolls, and adapted for rolling the interiorly extending portion of said ring against said ring member.

11. In a ring rolling mill, the combination 110 with the forming rolls, of an annular support rotated thereby adapted for sustaining a ring provided with a projecting portion and an axially movable flanging roll adapted for flanging said projecting portion against said support.

12. In a machine for rolling rings, a tapered 115 roll for engaging a side of the ring, a stepped tapered roll for engaging the opposite side of said ring, and interior and exterior rolls for 120

- engaging the peripheries of the ring, said rolls defining a closed way and having mutually overlapping parts.
13. In a machine for forming rings, relatively expansible and contractile rolls for engaging the periphery of a ring, and relatively adjustable tapered rolls for engaging the sides of the ring, said rolls being so constructed and arranged that they may be brought toward each other for rolling a ring with only a portion of the width of said rolls contacting said ring.
14. In a machine for rolling rings, two pair of oppositely disposed rolls defining a way for receiving a ring, one pair of said rolls being adjustable between the rolling surfaces of the other pair and means for adjusting said rolls.
15. In a machine for rolling rings, a slideable ring support comprising a plurality of adjustable shoes, rolling elements carried by said shoes, abutments in engagement with a pair of shoes and means for urging said ring support against said abutments.
16. In a machine for rolling rings, a slideable ring support having adjustable ring retaining elements, and a pair of abutments for limiting the sliding movements of said support, said abutments having curved surfaces so designed as to engage said elements in any adjusted position thereof.
17. In a machine for rolling rings, a slideable ring support, slideable shoes thereon, flanged rollers journaled in said shoes, means for adjusting said shoes, a pair of cam abutments for engaging a pair of said shoes, and means for automatically shifting said ring support and shoes against said abutments, said abutments engaging said shoes during all adjustments thereof.
18. In a ring rolling mill, the combination with the reducing and forming rolls thereof, of a ring support having adjustable ring sustaining devices thereon, means for simultaneously adjusting said devices, automatically operated means for adjusting said ring support with respect to said rolls during the adjustment of said devices, and a pair of cam abutments designed for engaging a pair of said devices in any adjusted position of said ring support.
19. In a rolling mill, a pair of oppositely disposed tapered rolls for acting upon the sides of a ring, a pair of opposed rolls for acting upon the exterior and interior peripheries of a ring, said rolls defining a closed way for concurrently acting upon substantially the same cross-section of the ring.
20. In a ring rolling mill, a roll for acting upon the side of a ring, a roll for acting upon the periphery of the ring, shiftable bearings for supporting said rolls, said bearing being in contacting relation and means for simultaneously shifting the same.
21. In a ring rolling mill, the combination with the forming rolls, of an annular support rotated thereby, said support being adapted for carrying a ring to be rolled, one of said forming rolls being shiftable transversely with respect to said ring.
22. In a ring rolling mill, the combination with the forming rolls, of an annular support rotated thereby, said support having a rabbet upon one face adapted for sustaining a ring to be rolled.
23. In a ring rolling mill, the combination with the forming rolls, of an annular support rotated thereby, said support being adapted for carrying a ring to be rolled by said forming rolls.
24. In a ring rolling mill, the combination with a plurality of rolls defining a closed ring pass, one of said rolls being shiftable transversely of the ring to be rolled, a support having adjustable elements for sustaining said ring and means for automatically adjusting said support during the adjustment of said elements.
25. In a ring rolling mill, the combination with the forming rolls, of a ring support having ring engaging devices, and a pair of sloping abutments for engaging a pair of said devices, and means for maintaining said pair of devices against said abutments for the purpose described.
26. In a ring rolling mill, a plurality of rolls defining a roll pass for rolling a ring and a smaller ring superposed thereon and projecting therebeyond, one of said rolls being transversely movable for flanging said smaller ring against one periphery of the larger ring.
- In testimony whereof I have hereunto subscribed my name.
- JAMES HALL TAYLOR.
